UNITED STATES PATENT OFFICE.

HENRY ALBERT CUTLER, OF BELFAST, IRELAND.

SCRAPER ARRANGEMENT FOR SEWERS AND THE LIKE.

1,220,075.

Specification of Letters Patent. Patented Mar. 20, 1917.

Application filed May 18, 1916. Serial No. 98,325.

To all whom it may concern:

Be it known that I, HENRY ALBERT CUTLER, a subject of the King of Great Britain and Ireland, residing at Belfast, in the 5 county of Antrim, Ireland, have invented Improvements in Scraper Arrangements for Sewers and the like, of which the following is a specification.

The object of the present invention is to 10 provide an improved scraper arrangement for removing, in a reliable and expeditious manner, deposit from sewers and other pipe or conduit systems.

To this end the scraper arrangement comprises a scraper blade so hinged to a drawbar or frame and having associated therewith position controlling means that the blade is caused to fold down against the drawbar or frame when the scraper is being drawn into a sewer or pipe and to take up an operative scraping position when the movement of the drawbar or frame is reversed in direction.

In the accompanying drawings Figures 1 25 and 3 are longitudinal sectional views of part of a sewer illustrating one arrangement according to the invention in the inoperative and operative position respectively. Fig. 2 is a plan corresponding to Fig. 1. Figs. 4, 5 and 6 are views similar to Figs. 1, 2 and 3 of a modification.

As shown in Figs. 1 to 3 inclusive, a blade *a*, *b* approximating in shape that of the interior cross section of the sewer *c* or the like 35 to be cleared, is offset in the region of a hinge boss *d* so that one portion *a* of the blade can be caused to lie flat against one side, and the other portion *b* of the blade flat against the opposite side, of a frame *e* 40 while the scraper is being inactively drawn into the sewer as depicted in Figs. 1 and 2.

The frame *e* (referred to in the claims as a draw bar) may advantageously comprise two side members splayed intermediate of 45 their length as at *f* to give a good hinge pin bearing and in contact with each other for a relatively great length at each end so as to constitute in effect a rod which will tend to remain more or less parallel to the 50 axis of the sewer when the scraper is being drawn into or out of it. *e*³ represents a distance tube mounted upon the hinge pin *g* and extending between the splayed portions of the side members of the frame. In 55 use it is preferred that the frame should occupy a position where one portion *b* of the blade is below and the other portion

a above it, the lower portion *b* being to the rear of the hinge pin *g* considering the direction in which the scraping is to be 60 done (see Fig. 3). In this way stop *h* can be provided upon both the blade portions *a*, *b*, or either thereof, which will find a rigid abutment against the frame *e* when the scraper is in use. If desired guards *p* 65 may be provided to prevent the scraper blade sinking into open joints in sewers or pipes.

The blade may be moved into and out of scraping position by connections made to 70 a pair of lines one of which, namely *i* is adapted to draw the scraper into the sewer and the other *j* to draw it out. For example a wire or chain *k* may be attached, as by a fitting *m*, to the upper scraper portion *a*, 75 near its topmost edge, the pull of the line *i*, that is to draw the scraper into the sewer, being transmitted to the scraper connection *k* which is shown as passing through an eye *n* at one end of the frame *e*. A similar 80 connection extends between the upper blade portion *a* and the opposite line *j* exemplified as a chain attached to the corresponding end of the frame *e*, such connection consisting of a tie *o* extending from some point 85 in the chain *j* to the blade.

The operation of the scraper is as follows:—

The line *i* is first passed through the section of sewer or pipe to be cleaned and attached to the connection *k* which passes through the eye *n* at the forward end of the bar or frame *e* and the chain *j* is attached to its after end, the scraper being then drawn into the sewer or pipe and the 90 pull of the line *i* keeping the blade flat against the bar or frame as shown in Figs. 1 and 2. When the scraper has arrived at its point of operation the pull on the forward line *i* is caused to cease and the scraper 100 is drawn back by the chain *j* which first rotates the scraper blade *a*, *b* about its hinge to a position at or nearly at right angles to the axis of the bar or frame *e* as shown in Fig. 3 and then draws the scraper with the 105 deposit to the point at which the scraper entered. The operation can be repeated indefinitely the scraper being pulled farther into the sewer or pipe as the deposit is removed, until the whole section is clear. 110

As will be understood the blade may have a regular edge and resemble a disk, or it may be formed with teeth; also the frame of the scraper may be offset instead of the blade;

while in lieu of or in addition to the upper half of the blade herein referred to, an extension arm may be employed with a roller at its upper extremity the distance of which 5 from the axis of the blade can be varied so as to alter the vertical diameter of the scraper. The connections to the various lines may extend from the roller pin on the arm, the purpose of the arm being to move 10 a blade into and out of operative position.

These various modifications are embodied in the example illustrated by Figs. 4, 5 and 6 where adjustable brackets a^1 constituting 15 an arm carrying a roller r extending above a toothed scraper blade b^1 have associated with the roller pivot pin s , a pair of links t to which the operating lines h and o are connected as through pins u . The frame e^1 is shown offset at e^2 .

20 What I claim is:—

1. Means of the kind described, comprising a draw bar, a scraper hinged thereto, lines for moving the draw bar alternately in opposite directions and position-controlling 25 means associated with the scraper, draw bar and lines, adapted to cause the scraper to fold down against the draw bar upon movement of the latter in one direction and to take up an operative scraping position when 30 the movement of the draw bar is reversed.

2. In combination, a scraper provided with a hinge boss, a draw bar having laterally splayed parts intermediate of its length to provide a hinge pin bearing, a hinge pin 35 connecting said scraper to such draw bar at the bearing, a pair of lines respectively associated with opposite ends of the draw bar, and means whereby movement of the adjacent end portion of either line in a direction 40 away from the draw bar will result in an angular movement of the scraper in relation to such draw bar.

3. In combination, a draw bar, a scraper pivoted to such draw bar, a line by which 45 the draw bar can be pulled in one direction, a line by which the draw bar can be pulled in the opposite direction and ties connected to the respective lines and adapted to impart an angular movement to the scraper in one 50 or other direction in relation to the draw bar as either of such lines is made taut.

4. In combination, a draw bar having an eye at each end, a scraper blade pivoted to such draw bar, a line fixed to one eye of the 55 draw bar, a tie between such line and the scraper, another tie extending in an opposite direction from the scraper and free to slide through the eye at the other end of the draw bar and a second line secured to the 60 end of such tie, substantially as described.

5. In combination, a scraper blade a draw bar comprising two side members splayed intermediate of their length to provide a

hinge pin bearing, a hinge pin connecting 65 said blade to such draw bar, a stop arrangement upon said scraper blade adapted to engage the draw bar and limit turning movement of the blade in one direction relative thereto, lines for moving the drawbar alternately in opposite directions and position 70 controlling means associated with the blade, draw bar and lines, adapted to cause the blade to fold down against the draw bar with movement of the latter in one direction and to take up an operative scraping position when the movement of the draw bar is 75 reversed.

6. In combination, a scraper blade a draw bar comprising two side members splayed intermediate of their length to provide a 80 hinge pin bearing, and offset in the region of such bearing a hinge pin connecting said blade to such draw bar, a stop arrangement upon said scraper blade adapted to engage the draw bar and limit turning movement 85 of the blade in one direction relative thereto, lines for moving the drawbar alternately in opposite directions and position controlling means associated with the blade, draw bar and lines, adapted to cause the blade to 90 fold down against the offset portions of the draw bar with movement of the latter in one direction and to take up an operative scraping position when the movement of the draw bar is reversed.

95 7. In combination, a draw bar, a scraper pivoted to such draw bar, a line by which the draw bar can be pulled in one direction, a line by which the draw bar can be pulled in the opposite direction a roller, 100 means adjustably connecting the roller to the scraper and ties connected to the respective lines and roller carrying means and adapted to impart an angular movement to the scraper through such means in one or 105 other direction in relation to the draw bar when either of such lines is made taut.

8. In a scraper arrangement for sewers and the like, a draw bar, a scraper hinged to said bar, guards connected to said scraper 110 adapted to prevent the same when in operative position from sinking into open joints in a sewer or the like, and means associated with said scraper adapted to cause the scraper to fold down against the draw bar 115 upon movement of the latter in one direction and to take up an operative position for scraping when the movement of the draw bar is reversed.

Signed at City Hall Belfast Ireland this 120 seventeenth day of April 1916.

HENRY ALBERT CUTLER.
